DESIGN FOR A NOVELTY BOX

Geraldine H. Jolley, San Francisco, Calif.

Application May 10, 1946, Serial No. 129,555

Term of patent 7 years

(Cl. D58—11)

To all whom it may concern:

Be it known that I, Geraldine H. Jolley, a citizen of the United States and a resident of the city and county of San Francisco, State of California, have invented a new, original, and ornamental Design for a Novelty Box, of which the following is a specification, reference being had to the accompanying drawing, forming a part thereof.

Fig. 1 is a perspective view of a box, showing my new design.

Fig. 2 is a perspective view of the other end of the box.

Fig. 3 is an end elevation of the box on a reduced scale in open position.

I claim:

The ornamental design for a novelty box, as shown,

GERALDINE H. JOLLEY.
